INVENTOR.

BY Joseph H. Miller
Charles B. Mann Jr.

ATTORNEY.

UNITED STATES PATENT OFFICE.

JOSEPH H. MILLER, OF HARRISBURG, TEXAS.

DISPENSING RECEPTACLE.

Application filed July 31, 1926. Serial No. 126,207.

This invention relates to improvements in dispensing receptacles and is particularly directed to a receptacle such as a can to contain fluids or substances that should be protected against unnecessary exposure to the atmosphere except when actually dispensing the contents.

The object of the invention is to provide an improved attachment for the closures of dispensing receptacles whereby the same may be held open by the hand during the actual dispensing operation but which when freed by the hand will at once move to a closing position.

Another object of the invention is to provide an improved attachment for the closures of receptacles whereby not only will the closure be guided and directed to the closing position over the nozzle with which it co-acts but at the same time will prevent the accidental detachment and the consequent liability of losing the closure by mislaying the same.

With these objects in view, the invention is illustrated in the accompanying drawing, wherein,

Fig. 1 shows a receptacle in side elevation to which the improved device is attached.

Fig. 2 illustrates a sectional detail through the upper wall of a receptacle and also through the nozzle therein and shows my improved device attached to the closure,—the latter being removed from the nozzle.

Fig. 3 shows the nozzle portion of the receptacle with the closure in place thereon and with the improved device depending therefrom, and

Fig. 4 illustrates the detached guide device in top view.

Referring to the drawing the numeral 5 designates the receptacle, which in this instance is presumed to be a sheet metal can. The shape of the can is immaterial and may be round or square.

The manner of constructing the can has nothing to do with my invention except that in the top wall 6 there is an ordinary sheet metal threaded nipple 7 having a flat top seat 8, and a handle 9 is attached to the top wall, which handle has a top surface 10 that is elevated above the said wall 6.

This closure cap carries a central depending stem 13, with an eye 14, at the lower end thereof, said stem preferably being rigidly connected to the closure cap so as to rotate

as the cap is turned when engaging or disengaging the nipple 7.

The eye 14 at the lower end of the stem sustains a weighted locking device which hangs freely and pendently from the said eye.

This weighted locking device is preferably formed from heavy wire and consists of a comparatively short vertical arm 15 having an eye 16 at the upper end to pivotally engage the eye 14 of the stem, and at its lower end carrying a loop 17, which extends in a direction crosswise of the arm.

This loop 17 is formed so that one side 18 thereof will extend laterally from the arm 15, a greater distance than the other side 19 thereof, and to this extent, the loop has the same function as has a similarly-shaped loop disclosed in U. S. Patent 1,570,270 heretofore granted to me.

The purpose of the loop is to prevent the direct withdrawal of the locking device through the nipple-opening but to permit withdrawal when the short side 19 is turned up to an inclined position and carefully drawn out through said nipple.

This obviously prevents the accidental loss of the closure-cap.

In the present structure however, the weight of the locking device and its pivoted or pendent attachment to the lower end of the cap-stem, are structural features that differ from the loop in my prior patent and also perform functions which the loop in said prior patent does not permit, as will presently be explained.

The closure-cap 11, and its stem 13, carry a guide device 20.

This guide-device is preferably formed from sheet metal and in this instance has an annular flat top flange 21; a series of depending arms or strips 22 and a concavo-convex bottom portion 23, at the lower ends of the depending arms.

This guide device is therefore of a substantially hemispherical shape and has its annular flange 21 seated inside the closure-cap while the arms 22 and bottom portion 23, project from the interior of the cap with the convex side of said bottom portion lowermost.

The stem 13 extends centrally through the bottom of the guide device and through the interior of the device itself.

A gasket 24, is carried in the cap at the

under side of the annular flange 21 and when the closure cap is screwed onto the nipple 7, this gasket seats on the flat seat 8 of the nipple and forms a tight seal.

5 By reference to Fig. 2, of the drawing it will be noted that when the closure cap is screwed onto the nipple 7, the guide device will depend through the nipple and project into the receptacle.

10 The stem 13 depends from the cap through the guide device and below the convex bottom into the receptacle, and as shown in Fig. 1 of the drawing, the weighted locking device, hangs pendently from the eye 14 at the 15 lower end of the stem.

When it is desired to pour a portion of the contents of the receptacle from the latter, the closure cap will be unscrewed from the nipple.

20 This unscrewing operation not only rotates the cap but also rotates the stem 13 and the locking device with its horizontally-disposed loop 17 and the turning of the loop serves to effect an agitation of the 25 contents of the receptacle.

When the cap is freed, it may be drawn upwardly and laterally, and I have found in practice that the most natural and convenient operation is to draw the cap toward the handle 9, as shown in Fig. 2 of the drawing because with one hand, the operator may readily hold the receptacle and also hold the cap to prevent it from sliding back toward the nipple during the pouring operation.

30 As soon as the pouring operation is over, the mere release of the cap from the hand will enable the weighted locking device to pull the stem 13 down through the nipple and (as indicated by broken lines in Fig. 2) and 40 the convex bottom 23 of the guide device will ride over the seat 8 of the nipple and direct the cap back over the nipple as the stem is pulled back into the receptacle, and thereby cover the nipple-opening.

45 This automatic operation of returning the cap to the nipple, covers the latter and prevents dust, dirt or bugs from entering the receptacle, and should the operator neglect to screw the cap down tight the latter will 50 at least cover the nipple and protect the contents against the entrance of outside matter.

In practice, the return of the cap to the nipple will be effected whether the same is held on the handle or not, but the operation is more readily carried out by drawing the cap over and on top of the handle.

Having described my invention, I claim,

1. The combination with a dispensing receptacle having an outlet in a wall thereof above the bottom, of a closure for said outlet, means attached to the closure and extending into the receptacle for drawing the closure toward said outlet and guide means also at-

tached to and moving with the closure for 65 directing the closure over the edge of the receptacle outlet, said guide means being in addition to the drawing means.

2. The combination with a dispensing receptacle having an outlet in a wall thereof above the bottom, of a closure for said outlet, weighted means attached to and sustained by the closure and hanging pendently in the receptacle, said weighted means being shaped to prevent its direct withdrawal 75 through the receptacle outlet and being heavy enough to draw the closure toward the receptacle outlet when the closure has been detached from the outlet, and guide means attached to and moving with the closure for directing the latter over and in register with the receptacle-opening when the closure is released.

3. The combination with a dispensing receptacle having a pouring nipple in a wall 85 thereof above the bottom, of a closure shaped to fit said nipple, weighted means hanging pendently in the receptacle and attached to the closure, said weighted means being shaped to prevent its direct passage through 90 said nipple and a guide device carried at the under side of and movable with the closure and shaped to enter the nipple, said guide device when the closure is released by the hand that held it open directing the closure into register with the nipple-opening as the weighted means draws it back.

4. The combination with a dispensing receptacle having a pouring nipple in a wall thereof and also having a raised and fixed 100 handle attached to the same wall at one side of the nipple, of a closure for said nipple, means attached to the closure and entering the receptacle for drawing the closure toward the nipple, said attached means being of such length as to allow the closure to be drawn to one side and held on the handle by the same hand which grasps the handle to tilt the receptacle, and means attached to and depending from the closure for guiding the closure into register with the nipple when the closure is released by the hand.

5. The combination with a dispensing receptacle having a screw-threaded nipple projecting from a wall thereof above the bottom, 115 of a screw-threaded flanged closure to engage said nipple, a stem attached to the closure and passing through the nipple into the receptacle, a weighted lock-device pendently attached to the stem and a hemispherically-shaped guide device projecting from the under side of the flanged closure and about the stem for directing the closure over the nipple when the weighted lock-device pulls the stem into the receptacle.

120 In testimony whereof I affix my signature.

JOSEPH H. MILLER.
